UNITED STATES PATENT OFFICE.

FREDERICK E. ARROQUIER, OF WORCESTER, MASSACHUSETTS, ASSIGNOR OF ONE-HALF TO DANIEL HENNIGAN, OF WORCESTER, MASSACHUSETTS.

MECHANISM FOR AFFIXING WINDOW-PATCHES ON ENVELOP-BLANKS.

1,250,075.

Specification of Letters Patent. Patented Dec. 11, 1917.

Application filed July 26, 1917. Serial No. 182,920.

To all whom it may concern:

Be it known that I, FREDERICK E. ARROQUIER, a citizen of the United States, residing at Worcester, in the county of Worcester and State of Massachusetts, have invented certain new and useful Improvements in Mechanism for Affixing Window-Patches on Envelop-Blanks, of which the following is a specification.

10 My invention relates to a novel mechanism for affixing transparent patches to envelop blanks for the manufacture of what are known as "outlook" or "window" envelopes, of the class in which an opening in the front 15 of the envelope has a strip of transparent material placed across the opening and secured to the inner surface of the envelope; the prime object of my present invention being to provide a convenient, practically efficient 20 organized means, as an attachment for envelop-machines, and adapted for affixing transparent strips or patches to the envelop blanks while upon the supply pack or elevator plate at the front of the machine, and 25 previous to the blanks being fed or transferred to the gumming and folding appliances of the envelop-forming machine.

A further object is to provide a mechanism of the character described adapted for 30 attachment, at a conveniently accessible position, upon the front of an envelop machine of well known construction, and which while affording means for the manufacture 35 of outlook envelopes will not materially interfere with the manufacture of plain envelopes upon said machine.

Another object is to provide an organized 40 means for automatically carrying the end of a continuous strip of transparent material over the supply pack of envelop blanks resting upon the supporter or elevator platform, at the same time applying gum upon the envelop blank, severing a patch from the strip and simultaneously affixing the same to the 45 topmost blank upon the pack, and means for transferring or feeding said patched blank from the pack to mechanism for seal-gumming and folding said blank into envelop form.

50 The nature, objects and preferred embodiment of my invention are set forth and explained in the following detailed descrip-

tion, with reference to the accompanying drawings, the particular subject matter claimed being definitely expressed in the 55 summary.

In the accompanying drawings, Figure 1 represents a top plan view of mechanism embodying my invention, and showing its relation as applied to an envelop machine. 60 Fig. 2 is a front elevation view of the same. Fig. 3 is a back view of the mechanism looking in an opposite direction to that of Fig. 2. Fig. 4 is a vertical section at line X-X on Fig. 1. Figs. 5, 6 and 7 are detail cross-sectional views, showing the reciprocating carrier, vertically moving plunger, and paper gripping means at different positions of their action. Fig. 8 represents a longitudinal vertical sectional view of the reciprocating carrier, patch-delivery bed, and gumming devices. Fig. 9 is a sectional view showing the plunger at position above the delivery bed. Fig. 10 is a cross-sectional view showing the gum-applying rolls. Fig. 75 11 is a separate view of the patch cutter on the end of the plunger. Fig. 12 is a view of an envelop blank with a patch thereon.

In the drawings only such portions of an envelop machine are shown, as will suffice 80 for illustrating the relation of my improved patch-affixing attachment in respect to said machine; since the structure of the envelop machine proper is not a part of my present invention; but it will be understood that an 85 envelop machine of any well known and suitable construction is herein referred to for the purpose specified. A indicates the table and frame of such machine; B the position of the creasing and folding box; C 90 the main operating shaft, and D the seal-gumming roll, located substantially as heretofore employed.

In the preferred embodiment of my present invention, there is arranged across the 95 front of the machine, conveniently above the elevator platform or plate 10 upon which the supply pack of envelop blanks E is supported, a suitable horizontal guide-way 11, preferably consisting of a pair of grooved 100 bars supported at or near their ends by suitable standards fixed to the machine frame A. Mounted in or upon said guide-way is a reciprocating carrier 12 having a vertically

moving plunger 13 fitted therein. The lower end of said plunger is formed as a rectangular plate 14 with a flat under surface approximately conforming to the shape and size of the required transparent patch to be affixed. The sides of the carrier 12 are provided with flanges that fit the guide-way grooves and slide freely therein. The carrier is connected by a rod 15 and pivotally attached link 15' to one arm of an angle lever 16 fulcrumed upon the stationary frame A, and having its opposite arm actuated by suitable connecting means from a cam 17 arranged upon the operating shaft C of the envelop machine, or by other efficient means, whereby reciprocating motion is imparted for moving the carrier 12 and parts mounted thereon, from the position shown in Figs. 1, 2 and 8 to the position shown in Fig. 9, and vice versa.

A spring 18 is provided for normally elevating the plunger 13 within the carrier 12. Said spring is preferably an expanding coil arranged about the neck of the plunger and confined between a supporting shoulder and a collar secured on the plunger, as indicated in Fig. 8. The plunger 13 is prevented from swinging out of alignment laterally, by a vertical pin 19 or equivalent guiding means engaging with the body of the carrier. I also provide upon the carrier 12, means for applying gum or adhesive substance to the envelop blank at the same time that the patch is advanced to position for attachment thereon: said means being more fully hereinafter described.

Numeral 20 indicates a patch-delivery bed, consisting of a stationary member having flat top surface occupying a position beneath that of the plunger-plate 14 when the latter is at the extreme end of its outward movement, as in Fig. 9. The patch material, or strip of transparent paper P, is drawn longitudinally across said bed 20 from a supply roll of the same, mounted on an axis stud 21 fixed in a suitable bracket at the side of the machine, and within convenient reach of the attendant. The sides of the bed 20 are preferably provided with upright or inwardly overhanging guide flanges between which the strip is guided longitudinally; and a transverse groove 23 is formed in the bed at a distance from its end equal to the determined length of the patch. The patch-delivery bed is best formed hollow, or with interior air passages 24, with openings leading thereto from its face. A suction pipe 25 connects said interior with any approved means (not shown) for exhausting air therefrom, to temporarily suck the paper strip down upon the bed. Any convenient friction means may be combined with the roll or strip P for giving tension thereon, or for preventing too rapid unwinding of the strip.

At one end of the plunger plate 14 there

is provided a transversely disposed perforating means, preferably comprising a thin steel plate 7 having a series of points or detents 8 along its lower edge, (see Fig. 11) adapted for partially severing the patch-forming strip P of transparent paper, as hereinafter described. Said detented plate is best attached to a reinforce block 27, the ends of which are fitted to freely slide up and down in grooves formed in longitudinally projecting ears upon the plunger plate. The extent of independent movement of said perforator means, in relation to the plunger plate, is limited by screws or studs 28 that pass through slots suitably formed through said parts. The lower edge of the reinforce block 27 is formed square, or adapted to serve as a clamping means against the end of the bed 20, for temporarily holding the strip P as the patch is severed therefrom. The perforator means is normally depressed by a suitable spring, or springs 29, the tension of which is sufficient to press the perforating points into or through the patch-forming strip.

In connection with the plunger-plate 14, at or near its end opposite that on which the perforator means is located, I provide a pair of grip members or nipper devices 2 for seizing the opposite edges of the patch-forming strip, and for drawing it forward over the envelop blank. Said nippers are preferably arranged as best illustrated in Figs. 5, 6 and 7. A nipper or jaw 2 is arranged at each side of the plunger-plate: and each being of similar structure a description of one will equally apply to both. The nipper jaw 2 is fulcrumed upon the outer end of a swinging link 3 which has its inner end pivoted to the plunger plate. Said jaw has an inwardly offset lip at its lower end. A latch-bar 4 is pivoted to the jaw 2 below its fulcrum and adapted for alternate engagement at its inner upturned end with a pair of notches formed on a block 5 attached to the plunger-plate. A spring 6 is arranged to press downward upon the link 3, and a spring 6' is arranged to press upward on the latch-bar, substantially as indicated. The inwardly offset lip serves for clamping the edge of the strip P against the under face of the plunger-plate. (see Fig. 5) and the outwardly offset lip serves for engaging with a lug or detent 9 attached to the guide-way bar 11 for retracting or releasing the grip of the nipper (see Fig. 6) when the patch is affixed. When the nipper is at holding position the latch-bar 4 engages the inner notch and when the nipper is thrown off the latch bar engages with the outer notch: thus retaining the nipper jaw in its latest position of adjustment until it is again shifted in the regular order of the operation.

Combined with the carrier 12 I provide

an upwardly and downwardly movable frame 30 in the lower end of which are mounted gum-applying rolls 31 and 32; while in its upper part there is arranged a 5 cross-bar having projecting ends with rollers 33 thereon that engage with guides 34 mounted upon the main guide-ways 11. (See Figs. 1, 8, 9 and 10.) The side bars of the frame 30 are preferably slotted and supported upon anti-frictional guiding rollers 35, the axes of which are fixed to the carrier so that the frame, with the gum-applying rollers, easily move in vertical direction. The guides 34, for controlling the vertical 10 movement of the frame and gum-applying rollers are each formed with an inclined lug 36 and an overlying spring 37 arranged so that when the carrier moves forward the supporting rollers 33 travel 15 along the top of the guides, thus keeping the gum-applying rolls elevated away from the envelop blank; but at the end of the guides they drop and in returning to first position the supporting rollers 33 run under the 20 guides 34, thereby causing the gum-applying rollers to travel upon the blank for depositing gum thereon, until the supporting rollers run up the inclines 36 and pass to the upper level, raising the springs 37, which 25 drops back to place in rear thereof, and lifting the gum-applying devices from contact with the blank.

The gum-applying rolls 31 and 32 are each formed with three rims which respectively place a line of gum upon the envelop blank, along the edges and at the ends of the window opening. The gum-roll 32 is made of small diameter, so that it can act closely adjacent to the end of the plunger 40 plate 14 to apply gum to the blank at the extreme end of the window opening, or beyond the position that could be reached by a roll of larger diameter, such as the roll 31; while the latter roll is adapted for doing 45 the principal part of the gumming. The rolls 31 and 32 contact with each other and both with the surface of the blank. The smaller roll receives its charge of gum from the larger roll 31. The bearing openings in 50 the frame 30, for the journals of the gum-applying rolls, are made larger, up and down, than the diameter of the journals, so that the rolls are in a degree self-adjustable to any irregularities or unevenness at the 55 top of the pack of blanks.

40 indicates an endless traveling belt mounted in alinement with the reciprocating carrier, upon pulleys 41 and 42 the axes of which are supported upon stationary portions of the machine; and 43 indicates a 60 gum-distributing roll mounted in peripheral contact with said belt. The axles of the rolls 41 and 43 are operatively connected by spur gears 44 and are driven by gears 45 in connection with a rotary shaft or stud 46

that receives its motion by a belt 47 (see Fig. 3) from the feed roll shaft 49, or any convenient part of the machine.

50 indicates a gum supply reservoir, having nozzles or orifices from which gum or adhesive substance can drip upon the roll 43, which transfers it to the belt 40 and said belt in turn spreads it in a thin film upon the faces of the applying roll 31.

51 indicates a receptacle beneath the roll 75 and belt for catching any gum that might drip therefrom. A scraper device 52 is provided for the gum-distributing roll 43, for regulating the film of gum applied to the belt. 80

54 indicates a rod or shaft supported by the housings or standards A¹ and extending parallel to the carrier-guide-way 11, somewhat to the rearward thereof, and having mounted thereon two tappet levers or members 56 and 57 adapted to be swung down upon the plunger head for depressing the plunger-plate 14; one of said tappet levers being positioned over the patch-delivery bed and the other positioned over the blank supporting plate 10; and 59 indicates a rotatable cam-shaft turning in bearings on the end standards A¹ adjacent to the shaft 54, and having cams 60 and 61 mounted thereon and severally adapted for operating the respective tappet levers. (See Figs. 1 and 4.) The top of the plunger 13 is preferably provided with a roll for receiving the contact of the tappet arms. Suitable springs are connected with the tappet lever heads 100 to keep them against their cams. The shaft 59 is operated by gears 62 and the inclined shaft 63, which latter may be connected by a suitable train of gearing with the main shaft of the envelop machine, or by other 105 approved power-applying means.

Mounted upon the shaft 59 there is a depending backwardly and forwardly swinging pick-up device 65, best shown in Figs. 3 and 4, having a slotted bearing upon the 110 shaft to permit up and down movement; and a tubular lower end connected by a pipe 67 with a suitable air exhausting means (not shown.) This pick-up device is joined by a pivotedly attached link 68 115 to the lower end of a lever 69 fulcrumed upon the shaft 54, and actuated by a cam 70 mounted upon cam-shaft 59. A cam 71 is also arranged for moving the device 65 up and down. The function of this pick-up device is to lift the edge of the patched envelop blank from the top of the pack E by suction, and to swing said blank into the bite of the feeder-rolls 72 and 73 that feed it to the advancing or seal-gumming rolls 120 D of the envelop machine, which take it on its way to the folding mechanism to be creased and folded in well known manner.

The upper feed roll 73 is formed of two short roll sections mounted to revolve upon 130

stationary studs or arbors 74 with a space between their inner ends to accommodate the swinging lower end of the pick-up device 65. The lower feed-roll 72 is made full 5 length and fixed upon the revolving shaft 49, which is operated by suitable gearing 75 in connection with the envelop machine mechanism.

The pack of envelop blanks E is arranged 10 between suitable upright guide-pins 76 upon the table or platform 10, which is supported by a bracket 10^a that is adjustable up and down, and which may be the usual pack-supporting elevator of the envelop machine, 15 or its equivalent. An automatic regulating mechanism 78, controlled by a reciprocating rod and evener device or feeler 79 acting against the top of the pack, is provided for keeping the upper surface of the pack at a 20 given level for receiving the action of the patch-applying means.

To insure accurate registering of the plunger-plate 14 with the strip-delivering bed 20 and blank-supporting platform 10 at 25 the respective limits of the reciprocative carrier movement, I provide the plunger plate with a projecting vertically grooved member or lug r for engagement with register-guards i and o attached to the carrier-supporting guide-way 11, see Fig. 2. Said 30 guards are formed with inwardly offset lower ends that engage the grooved member r only when the plunger is at partially depressed position; but leave the parts free for 35 endwise reciprocation while the plunger is in elevated position.

In the operation: Assuming that the gumming devices are charged with suitable adhesive material; that a rolled strip of trans- 40 parent paper of the proper width is supported upon the stud 21; and that the end of said strip is drawn over the bed 20 where it is temporarily retained by the air pressure. The reciprocation of the carrier 12 moves the plunger-plate 14 and gum-applying rolls from the primary position (see Fig. 8) to a position (Fig. 9) where the plunger-plate 14 is over the bed 20. The tappet 57 is then actuated to press the 45 plunger-plate down upon the delivery-bed and strip P, causing the perforator 7 to pierce the strip above the groove 23, while the nippers 2 are caused to clamp the end of the strip against the plunger-plate. At 50 the same time the roll-bearing frame 34 drops from the end of its guide 34 letting the gum-applying rolls 31 and 32 (which have been carried to the farther end of the window opening) down to rest upon the 55 surface of the topmost envelop-blank E. Then as the carrier moves toward its former position the gum-applying rolls travel along the surface of the blank, depositing the lines of gum thereon, and the patch-forming strip 60 P is drawn forward by and with the plunger- 65

plate until the end portion thereof and plunger-plate are at a position centrally over the opening in the envelop blank. The plunger is then forced down by the tappet 56 and its actuating means, thereby causing 70 the patch beneath the plunger-plate to be pressed down upon the gummed blank to which it adheres. Also, simultaneously with the downward movement, the reinforce block 27 clamps the strip P firmly against 75 the end of the delivery bed 20 adjacent to the perforator plate 7, and the portion of said strip to form the patch is severed, torn or detached therefrom along the line of perforations, and pressed upon the blank by the 80 movement of the plunger. As the plunger-plate descends, bringing the patch near the blank, the nippers 2 are released by their upper end contacting with the detents 9; and the latch bars 4 keep them distended 85 while the plunger is raised to its primary position. The leading edge of the blank is then lifted by the pick-up device 65 and started on its way through the rolls for the seal-gumming and folding operations, leaving the top of the pack clear for repeating 90 the operation of affixing a patch, in like manner, to the next succeeding topmost blank on the pack.

After the patch is detached from the strip 95 and the end of the latter released by the lifting of the block 27 therefrom, the strip is retained in position upon the bed until the plunger-plate again descends thereon, by air pressure, or the exhaustion of air, 100 through the bed by any suitable well known apparatus.

I claim and desire to secure by Letters Patent—

1. In combination, with an envelop-blank supply-holder in an envelop machine; of a laterally disposed guide-way above said blank-supply-holder, a reciprocating carrier movable on said guide-way, a vertically movable plunger mounted in said carrier 105 and having a plunger-plate at its lower end, a delivery-bed for presenting the end of a paper strip in line with said plunger-plate, means for temporarily connecting said strip and plunger-plate, means carried by said plate for severing the strip, means for reciprocating the carrier to bring said plunger alternately into vertical alignment with said blank-supply-holder and with said delivery-bed, and means for depressing the plunger 110 at each of said positions.

2. In combination with a holder adapted for supporting outlook-envelop blanks, a horizontal guide-way above said holder, a reciprocating carrier movable on said guide, 125 means for operating said carrier, a vertically movable plunger mounted on the carrier, a strip-delivery means for presenting a patch-forming strip to the plunger-plate, means for moving said plunger up and 130

- down within the reciprocating carrier, a gum-applying roll, a supporting frame therefor mounted upon the carrier, means for keeping said roll elevated while the 5 carrier moves in one direction, and means for depressing said gum-applying roll to run upon the envelop blank when the carrier moves in the other direction.
3. A patch-affixing attachment for envelop 10 machines, comprising a support for a pack of envelop-blanks, a reciprocating carrier, a patch-applying plunger and gum-applying devices mounted upon said carrier to alternately move over the pack of blanks, guiding 15 means for said carrier disposed above the blank-supporter transverse to the direction in which the blanks are fed from the pack, means for delivering a strip of transparent paper from which the patch is taken 20 by said plunger, at one end of the guide-way, means at the opposite end of the guide-way for delivering gum to said gum-applying devices, means for depressing the plunger at positions for receiving and for affixing 25 the patch, means for controlling the action of the gum-applying devices, and means for imparting reciprocative movement to said carrier synchronous with the action of the envelop machine.
- 30 4. In mechanism for affixing patches to envelop-blanks of the class specified, means for supporting a pack of envelop-blanks, a horizontal guide-way above said support, a reciprocating carrier movable along said 35 guide-way, a vertically movable plunger mounted in said carrier and having a plunger-plate at its lower end approximately corresponding to the size of a patch, a spring-pressed perforator arranged upon one end 40 of the plunger-plate, nipper devices arranged at the other end of said plate, a spring for normally elevating said plunger within the carrier, means for supporting a strip of patch-forming material, a strip-delivery-bed in line with and below the plunger-plate, a top shaft, tappet levers thereon for depressing said plunger at predetermined 45 positions, an adjacent operating shaft provided with cams for respectively actuating said tappet levers, and means for imparting reciprocal movement to the carrier.
5. In mechanism for affixing patches to envelop-blanks of the class specified, in combination with blank-supporting means, reciprocating carrier, patch-applying plunger, and carrier-supporting guide-way; of gum-applying rolls adapted for depositing lines of gum or adhesive substance upon the top-most blank adjacent to the edges of the 55 opening therein, a bearing frame for said gum-applying roll mounted to have up and down movement upon said reciprocating carrier, guide-engaging means upon said bearing frame and supplemental guides 60 therefor adapted for shifting the level of 65 said gum-applying rolls to pass clear of the blank when the carrier moves in one direction and to contact with the blank when the carrier moves in the other direction, and means for charging said rolls with gum. 70
6. In a mechanism for affixing patches to envelop blanks, in combination, a support for a pack of blanks, and means for delivering a strip of patch-forming material, means for applying gum to the blank, 75 means for perforating the patch-forming strip on a line across the same, indicating the length of the patch, means for carrying the end of the strip over the blank, means for pressing the same upon the gummed 80 blank and simultaneously detaching the patch from the strip along the line of perforations.
7. In a mechanism for affixing patches upon envelop blanks, the combination, with 85 a support for a pack of blanks, and a horizontally reciprocating carrier having gum-applying devices, and a vertically movable plunger carried thereon; of means for supporting a rolled strip of patch-forming paper, a strip-delivery bed formed hollow with openings in the face thereof, means for perforating the strip carried upon said plunger, means for temporarily clamping the strip to the plunger-plate for advancing it over the 90 blank, means for depressing the plunger to detach the patch from the strip and apply it to the blank, and means for pneumatically holding the end of the strip upon the delivery-bed. 95
8. In mechanism of the class specified, the combination, with a support for the blanks, a reciprocating carrier, a guide for said carrier over the blank supporter, a patch-applying plunger mounted in said carrier, and 100 means controlling the action of said plunger; of a gum-applying means mounted upon said carrier adjacent to said plunger, and including an upwardly and downwardly movable frame having a pair of contacting gum-applying rolls journaled in the lower part thereof, one of said rolls being of small diameter and the other of larger diameter, means for lifting and depressing said frame and rolls in relation to the plane of the carrier movement, a gum-delivering means with which said larger roll contacts by movement of the carrier, and means for reciprocating the carrier. 110
9. In a mechanism for the purpose described, a support for blanks, a horizontally movable carrier, a guide-way for said carrier disposed across and above said support, a vertically movable patch-affixing plunger mounted in said carrier, gum-applying 115 means movable with said carrier, means for moving the carrier horizontally, means for delivering a strip of patch-forming fabric beneath said plunger, means for depressing the plunger at the respective positions for 120 125 130

receiving and for applying the patch, an upwardly and downwardly movable backwardly and forwardly swinging pick-up device adapted for lifting and advancing the 5 edge of the patched blank, and feed-rolls that take said blank from the pick-up device.

10. In mechanism of the character described, including a supporter for blanks, a reciprocating carrier, a guide for said carrier horizontally crossing the blank supporter, and a patch-applying means; the combination with a gum-applying roll mounted to move with said carrier; of a traveling gum-distributing endless belt in 15 approximate alinement with said carrier, pulleys for supporting the belt, said gum-applying roll adapted to contact with said belt by reciprocal movement of the carrier, a gum-supply reservoir, means for depositing 20 gum upon said belt, means for operating the traveling belt, and means for reciprocating the carrier.

11. In a mechanism of the character described, the combination, with means for 25 supporting a pack of envelop-blanks having openings therein, means for applying gum to the blank along the edge of the opening, and means for delivering and affixing the transparent patch upon the gummed blank; 30 of a pneumatic pick-up device, comprising a backwardly and forwardly oscillating member, a shaft wherein said member is supported to also have up and down movement; means for imparting oscillating 35 movement to said pick-up device and upper and lower rotating feed rolls into which the edge of the blank is inserted by said pick-up device, the upper roll being formed in two sections with intervening space to accom-

modate the swing action of the pick-up 40 member.

12. In a mechanism for the purpose described, the combination, with a patch-delivering bed, a blank supporting means, a laterally reciprocating carrier, a carrier-guide, a vertically movable plunger provided with a patch-applying plunger-plate mounted in said carrier, and means for operating said parts; of a register guard comprising lugs or engaging members attached to said 50 plunger-plate, and counter-engaging members attached to the stationary guide and positioned to respectively correspond with the positions of the patch-delivery and blank support; said guard members being adapted 55 to permit reciprocation of the carrier and plunger when the plunger is elevated, but to intermeshingly engage when the plunger is depressed at either of the registering positions. 60

13. In a mechanism for the purpose described, the combination, with a stationary strip-delivery bed having a transverse groove, a movable plunger-plate adapted for taking and applying a transparent patch to a blank; of a spring-pressed perforator-plate having points adapted for perforating the strip at said transverse groove, and a reinforce block combined with said perforator plate, said reinforce block adapted for holding the end of the strip against the delivery-bed to facilitate the detachment of the patch along the perforated line when the plunger-plate is depressed for applying the patch upon the blank. 70

75 Witness my hand this twenty fifth day of July, 1917.

FREDERICK E. ARROUQUIER.
